UNITED STATES PATENT OFFICE.

BENJAMIN V. KERSHNER, OF KANSAS CITY, MISSOURI, ASSIGNOR TO UNION SPECIAL MACHINE COMPANY, OF CHICAGO, ILLINOIS, A CORPORATION OF ILLINOIS.

WAISTBAND FOR TROUSERS.

Application filed March 22, 1920. Serial No. 367,966.

To all whom it may concern:

Be it known that I, BENJAMIN V. KERSHNER, a citizen of the United States, residing at Kansas City, in the county of Jackson, State of Missouri, have invented certain new and useful Improvements in Waistbands for Trousers, of which the following is a description, reference being had to the accompanying drawing and to the figures of reference marked thereon.

The invention relates to new and useful improvements in trousers, and more particularly to the waist band construction thereof.

An object of the invention is to provide a waist band construction which includes a stiffening strip and a lining strip, and wherein these parts are secured to the body fabric of the trousers above the upper edge thereof, by stitches which are concealed from view at the inside of the garment parts.

Another object of the invention is to provide a construction wherein the belt loop is also secured by the stitches which join the lining strip, body fabric and stiffening strip.

A further object of the invention is to provide a waist band construction wherein the lower edge of the lining strip and the stiffening strip are secured to the body fabric by through-and-through stitches, and wherein a tacking strip is provided to which the belt loop may be secured by stitches which are concealed from view at the inside of the garment parts by the covered lower edge of the stiffening strip.

A still further object of the invention is to provide a new method of forming waist bands wherein the waist band proper, belt loop and suspender buttons are first secured to the upper edge of the body fabric of the trousers, after which the lower part of the waist band is secured to the garment, and the belt loops secured to a tacking strip by tacking stitches.

These and other objects will in part be obvious and will in part be hereinafter more fully disclosed.

In the drawings, which show by way of illustration one embodiment of the invention.

Figure 1 is a view showing in section and in elevation a waist band construction embodying my invention;

Fig. 2 is a view showing the waist band proper secured to the body fabric, the belt

loop also secured to the waist band construction, and the buttons sewed to the waist band construction;

Fig. 3 is a similar view, but showing the body fabric as having been folded against the waist band and secured thereto by stitches passing through the lower portion of the waist band;

Fig. 4 is an inside view of a portion of the completed waist band.

The invention consists broadly in providing a waist band for trousers which includes a stiffening strip having a binding covering the lower edge thereof, a lining strip having its upper and lower edges inverted, and a tacking strip, the lining strip and stiffening strip, and the extreme upper edge of the body fabric of the trousers being united by a line of stitching passing therethrough, and in the preferred form of the invention a belt loop is inserted between the inverted edge of the body fabric and the lining strip and is secured by said line of stitching. The suspender buttons are sewed to the lining strip, the stiffening strip, and preferably to the belt loop. A binding strip is placed about the lower edge of the stiffening strip. A tacking strip is placed against the face of the binding strip, and the lower edge of the lining strip, the binding, the stiffening strip and the tacking strip are stitched together.

In carrying out my new method, the parts above described are stitched in the manner stated, after which the body fabric is folded over the edge of the stiffening strip and against the inner face thereof, and a line of stitching is passed through the binding, the stiffening strip, the tacking strip and the body fabric, just below the lower edge of the lining strip. The belt loops are then folded over the edge of the body fabric and are secured by tacking stitches to the body fabric and tacking strip only.

Referring more in detail to the drawings, I have shown the invention as applied to trousers, the body fabric of which is indicated at 1. The lining strip is indicated at 2. The upper edge of the lining strip is inverted, as indicated at 3, and the lower edge is inverted, as indicated at 4. A belt loop 5 has its upper end placed against the body fabric 1, and then the lining strip is placed against the belt loop and the face of the body fabric 1. A stiffening strip 110

2
is indicated at 6, and this is placed on the other side of the body fabric, after which a line of stitching, indicated at 7, is passed through the upper infolded edge of 5 the lining strip, the belt loop, the body fabric, and the upper edge of the stiffening strip. A binding, indicated at 8 in the drawings, is folded about the lower edge of the stiffening strip, a tacking strip 9 is placed against the binding, and a line of stitching, indicated at 10, is passed through the lower infolded edge of the lining strip, the binding, the stiffening strip and the tacking strip, uniting the same.

15 A button, indicated at 11, is sewed to the lining strip and stiffening strip, as indicated in Figure 2 of the drawings. After the parts have been formed, as described above, the body fabric 1 is folded around the upper 20 edge of the stiffening strip, and against the inner face of the tacking strip, after which a line of stitching 12 is passed through the binding strip, the stiffening strip, the tacking strip and the body fabric. 25 This stitches down the waist band so as to prevent the lining strip from creeping above the upper edge of the trousers, and also holds the lower part of the waist band firmly in place. The stitches uniting the upper 30 edge of the lining strip, the body fabric and stiffening strip are concealed by the body fabric. Likewise, the stitches uniting the lower edge of the lining strip, the stiffening strip and the tacking strip are concealed by 35 the body fabric so that there is only one line of stitching which passes through the body fabric at the lower portion of the waist band, and this is the line of stitching 12.

40 The lower end of the belt loop is inturned, as indicated at 13, and this is secured by tacking stitches 14 to the tacking strip only. The depending skirt formed by the bound edge of the stiffening strip may be raised from the tacking strip so as to permit the 45 insertion of these tacking stitches, and this depending skirt will cover and conceal the tacking stitches. Preferably the buttons are sewed on by threads passing through the belt loops, and this forms a very firm and durable fastening for the button, and the 50 threads which secure the button to the garment are concealed by the body fabric and at the same time are through-and-through stitches.

55 From the above, it will be noted that the invention is directed to a new improvement in a waist band construction for trousers, and also in the method of making the same, which method permits the construction of 60 the waist band and the attachment of the same to a garment largely, if not wholly, by machine stitching. In other words, the lining strip and the stiffening strip are secured together and to the body fabric and belt 65 loop before the body fabric is folded about

the edge of the stiffening strip and, therefore, these parts may be stitched on a sewing machine. The subsequent folding of the body fabric of the garment and the stitching of the same by a single line of stitching 70 passing therethrough results in a construction which very closely resembles the hand-sewed waist band.

It is obvious that minor changes in the details of construction may be made without departing from the spirit of the invention as set forth in the appended claims.

Having thus described the invention, what is claimed as new and desired to secure by Letters-Patent is:—

1. The combination of the body fabric of trousers, a stiffening strip at the waist band, said body fabric being folded over the upper edge of said stiffening strip, a lining strip placed against the inner face of the folded-over edge of the body fabric, and a line of stitching passing through said lining strip, said folded-over edge of the body fabric and the stiffening strip and concealed from view at the outer face of the garment 90 by the body fabric, a binding strip enclosing the lower edge of the stiffening strip, a line of stitching passing through the lower edge of the lining strip and through the binding strip and stiffening strip, and a second line 95 of stitching passing through said binding strip, stiffening strip and body fabric, a series of belt loops having their upper ends extending between the lining strip and the stiffening strip and secured by the line of 100 stitching joining the upper edges thereof, a tacking strip secured to the stiffening strip and binding strip by a line of stitches passing through the binding strip and stiffening strip, and stitches passing through the tacking strip, the body fabric and the lower end of the belt loops for securing the same.

2. The combination of the body fabric of trousers, a stiffening strip at the waist band over the upper edge of which the body fabric 110 is folded, a lining strip at the inner face of the folded-over edge of the body fabric, a belt loop having its upper end extending between the lining strip and the folded-over edge of the body fabric, a line of stitching 115 passing through the lining strip, belt loop, the folded-over edge of the body fabric and the stiffening strip and concealed at the outer face of the garment by the body fabric, a button secured to said lining strip and 120 stiffening strip by stitches concealed at the outer face of the garment by the body fabric, said stiffening strip extending below the lower edge of the lining strip, a binding strip covering the lower edge of the stiffening strip and extending above the lower edge of the lining strip, a tacking strip, a line of stitching passing through the lining strip, the binding strip, stiffening strip and tacking strip and concealed at the outer face 130

- of the garment by the body fabric, a line of stitching passing through the binding strip, the stiffening strip, the tacking strip and the body fabric, and tacking stitches passing through the tacking strip, the body fabric and the lower end of the belt loop. 50
3. The combination of the body fabric of trousers, a stiffening strip at the waist band, said body fabric being folded over the upper edge of the stiffening strip, a lining strip placed against the inner face of the folded-over edge of the body fabric, a line of stitching passing through the lining strip, said folded-over edge of the body fabric and the stiffening strip and concealed from view at the outer face of the garment by the body fabric, a binding strip enclosing the lower edge of the stiffening strip, a tacking strip at the rear of the binding strip, a line of stitching passing through the lower edge of the lining strip, through the binding strip and stiffening strip and through the tacking strip, and means for securing the tacking strip to the body fabric. 60
4. The combination of the body fabric of trousers, a stiffening strip at the waist band over the upper edge of which the body fabric is folded, a lining strip at the inner face of the folded-over edge of the body fabric, a belt loop having its upper end extending between the lining strip and the folded-over edge of the body fabric, a line of stitching passing through the lining strip, belt loop and the folded-over edge of the body fabric and the stiffening strip and concealed at the outer face of the garment by the body fabric, a button is secured to the lining strip and stiffening strip by stitches concealed at the outer face of the garment by the body fabric, said stiffening strip extending below the lower edge of the lining strip, a binding strip covering the lower edge of the stiffening strip and extending above the lower edge of the lining strip, a tacking strip, a line of stitching 70
- passing through the lining strip, the binding strip, stiffening strip and tacking strip and concealed at the outer face of the garment by the body fabric, and means for securing the tacking strip to the body fabric. 75
5. The method of making a waist band for trousers comprising stitching the upper edge of the body fabric of the trousers between the upper edges of a stiffening strip and a lining strip, placing a binding strip about the lower edge of the stiffening strip and stitching the lower edge of the lining strip, the binding strip and the stiffening strip and a tacking strip together, folding the body fabric over the edge of the stiffening strip, and stitching said stiffening strip, binding strip and tacking strip to the body fabric by a line of stitching passing therethrough below the edge of the lining strip. 80
6. The method of forming a waist band for trousers comprising inserting the upper edge of the body fabric of the trousers and the belt loop between the upper edges of a lining strip and a stiffening strip and securing said lining strip, belt loop, body fabric and stiffening strip by a line of stitches passing therethrough, placing a binding strip about the lower edge of the stiffening strip and a tacking strip against the face of the binding strip, and stitching the lining strip, binding strip, stiffening strip and tacking strip by a line of stitches passing therethrough, sewing a button to the lining strip and stiffening strip below the edge of the body fabric, folding the body fabric and belt loop about the upper edge of the stiffening strip, stitching the body fabric to the binding strip, stiffening strip and tacking strip by a line of stitching passing therethrough below the edge of the lining strip, and stitching the lower end of the belt loop to the body fabric and tacking strip. 85

In testimony whereof, I affix my signature.

BENJ. V. KERSHNER.
